UNITED STATES PATENT OFFICE.

FRANK BOGERD. OF OTTAWA, ILLINOIS.

TRACE-HOLDER FOR WHIFFLETREES.

1,171,499.

Specification of Letters Patent. Patented Feb. 15, 1916.

Application filed April 25, 1914, Serial No. 834,470. Renewed December 10, 1915. Serial No. 66,224.

To all whom it may concern:

Be it known that I, FRANK BOGERD, a citizen of the United States, residing at 819 Sycamore street, Ottawa, in the county of 5 La Salle and State of Illinois, have invented certain new and useful Improvements in Trace-Holders for Whiffletrees, of which the following is a specification.

This invention relates to improvements in 10 trace-attachments for whiffletrees.

The invention has for its object primarily to provide for readily attaching the trace or traces to the whiffletree, as well as like detachment of the trace therefrom.

15 A further object is to effectively guard against the casual disengagement of the trace or traces from the whiffletree.

A still further object is to carry out the aforesaid ends in a simple, economic and 20 effective manner, and with facility.

The invention therefore consists of certain structural features including the combination and arrangement of parts substantially as hereinafter fully disclosed and 25 defined by the appended claim.

In the accompanying drawing is illustrated the preferred embodiment of my invention, wherein it will be understood that various changes and modifications may be 30 made as to the detailed construction and arrangement of parts without departing from the spirit of the invention, and in which drawing—Figure 1 is a fragmental perspective view showing the application 35 of my invention in practical use. Fig. 2 is a detached side elevation of the device. Fig. 3 is a plan view of the parts, as shown, in Fig. 1. Fig. 4 is a section taken on the line 4—4 of Fig. 3.

40 In carrying out my invention, I suitably attach to a whiffletree A upon its upper surface, at each end, a suitable casting which may be termed a bracket designated as 1, with its attached end preferably formed 45 flat, as at 2, for the more effective retention thereof upon the whiffletree. Said casting or bracket is upraised the remaining portion of its length, as at 3, the upraised portion 3 extending parallel with the whiffletree with 50 its outer end terminating at a point nearly

in vertical alinement with the end of the latter. The upraised portion 3 of the bracket 1 is tubular or chambered, as at 4, its outer end being provided with a slot 5, and within the tubular raised portion of said bracket is 55 pivoted as at 6, a substantially right-angled lever or latch 7 with its vertical arm received within said slot, the horizontal arm of said latch initially engaging the upper surface of the tubular raised portion of said 60 bracket, said horizontal arm having a lower straight edge, as at 8, to effectively provide for such engagement. The pivoted latch 7, it will therefore be seen, is so positioned as to guard the entrance of the point of reception 65 of the trace, and to provide for the engagement of said latch by the trace in effecting the attachment of the latter with the whiffletree, said latch, as it is thus engaged by the trace, readily yielding inwardly to 70 allow the trace to pass, the latch immediately thereafter automatically filling and accordingly providing for the retention of the trace in secured position upon the whiffletree, as against casual displacement which 75 would otherwise be liable to occur in use.

It will be observed that, as the latch is carried inwardly in attaching the trace, the tubular portion of the bracket 1 will provide for the reception of the vertical arm 80 of said latch in providing clearance for the insertion of the trace. Also, it will be observed that the upraised portion of the bracket 1 provides not only for the reception thereunder of the trace, but also serves 85 to aid the retention of the trace in operative position upon the whiffletree, this however, being brought about by suitably spacing said upraised portion of the bracket from the latter with respect to the extent of the 90 trace positioned above the whiffletree, which is thought apparent.

I claim—

A whiffletree having a bracket secured thereto, upon its upper surface, said bracket 95 having an upraised portion with its outer end about in vertical alinement with the end of the whiffletree, said bracket upraised portion being chambered, the resultant chamber opening through the underside thereof, 100

and a latch pivoted in the outer end of said bracket upraised portion and right-angled in general outline with its horizontal arm positioned to initially rest upon said upraised portion of the bracket and its vertical arm to guard the entrance to the point of application of the trace.

In testimony whereof I affix my signature in presence of two witnesses.

FRANK BOGERD.
